BY *Chas. E. Spillman*
ATTORNEYS

UNITED STATES PATENT OFFICE.

JOHN A. HOLZAPFEL, OF JACKSON, MICHIGAN.

ANCHOR.

Application filed October 16, 1926. Serial No. 142,048.

This invention relates to improvements in anchors.

My present improvements are especially designed by me for embodiment in anchors of the type shown in my Letters Patent No. 1,493,489 issued May 13, 1924, in which a grapple member is loosely mounted upon the shank although readily adapted and desirable for use in other forms of anchors.

10 The main object of the invention is to provide an improved anchor in which desired weight, within certain limits, can readily be secured.

Objects relating to details and economies 15 of construction and operation will definitely appear from the detailed description to follow.

I accomplish the objects of my invention by the devices and means described in the 20 following specification. The invention is clearly defined and pointed out in the claims.

A structure which is a preferred embodiment of my invention is clearly illustrated in the accompanying drawing, forming a 25 part of this application in which:

Fig. I is a side view of my improved anchor.

Fig. II is a transverse section on a line corresponding to line 2—2 of Fig. I.

20 Fig. III is a side elevation of one of the weighting members.

Fig. IV is an inside view of one of the shank sections.

In the drawing similar reference characters refer to similar parts throughout the 35 several views.

Referring to the drawing, my improved anchor comprises a shank 1 and grapple member 2. The body portion of the shank 40 is upwardly tapered, having an annular shoulder or stop 3 at the bottom below which is a downwardly tapered tip 4. This shank is formed of a pair of complementary sections 5 having interfitting joint flanges 6 and 7 on their longitudinal edges. These sections are shell-like providing a chamber 8 having weighting material or members such as the sections 9 which are conformed to fit 45 within the weighting chamber.

50 The shank sections have opposed holes 10 adjacent their upper ends and opposed holes 11 adjacent their lower ends to receive the rivets 12 and 13 respectively, the rivet 12 being arranged through holes 14 provided therefor in the weight members 9.

A longitudinal bore 15 is provided at the upper ends of the shank sections to permit the introduction of filling material such as shot or slugs, or melted lead may be poured in if desired to secure the desired weight.

60 Rope eyes 16 are provided for the attachment of a rope.

The grapple member 2 rests upon the shoulder 3, it being preferably loosely mounted as is described in my said patent.

65 My improved anchor may be shipped in the knock down and without the weight if desired, the weighting material being inserted by the retailer or purchaser. This is especially advantageous in parcel post and 70 express shipments as the anchors are of necessity of considerable weight.

Having thus described my invention, what I claim as new and desire to secure by Letters Patent is:

75 1. An anchor comprising an upwardly tapered shank having a shoulder at its lower end and a conical tip below the shoulder, said shank comprising a pair of complementary longitudinal shell-like sections having 80 coacting joint flanges on their longitudinal edges, said sections having opposed rivet holes and opposed rope eyes at their upper ends, there being a longitudinal bore at the upper ends of said sections providing an 85 opening to the interior of said shank, connecting rivets for said sections disposed through said opposed openings, and a grapple member loosely mounted on said shank and adapted to normally rest on said shoulders.

90 2. An anchor comprising an upwardly tapered shank having a shoulder at its lower end and a conical tip below the shoulder, said shank comprising a pair of complementary longitudinal shell-like sections having 95 coacting joint flanges on their longitudinal edges, said sections having opposed rivet holes and opposed rope eyes at their upper ends, connecting rivets for said sections disposed through said opposed openings, and a grapple member loosely mounted on said shank and adapted to normally rest on said shoulder.

100 3. An anchor comprising an upwardly tapered shank having a shoulder at its lower end and a conical tip below the shoulder, said shank comprising complementary longitudinal shell-like sections providing a 105 weight chamber, there being a longitudinal 110

2
bore at the upper ends of said sections providing an opening to the interior of said shank to receive a weighting material, and a grapple member loosely mounted on said shank and adapted to normally rest on said shoulder.

4. An anchor comprising an upwardly tapered shank having a shoulder at its lower end and a conical tip below the shoulder, said shank comprising complementary longitudinal shell-like sections providing a weight chamber, and a grapple member loosely mounted on said shank and adapted to normally rest on said shoulder.

15 5. An anchor comprising an upwardly tapered shank having a shoulder at its lower end and a conical tip below the shoulder, said shank comprising a pair of complementary longitudinal shell-like sections, 20 weight members conformed to fit within said shank, a connecting rivet for said shank

sections disposed through said weight sections, and a grapple member loosely mounted on said shank and adapted to normally rest on said shoulder.

25 6. An anchor comprising a shank formed of a plurality of complementary shell-like sections providing a weight chamber, weight sections fitting within said chamber, means for securing said shank sections together comprising a rivet arranged through the shank sections and through said weight sections, and a grapple member on said shank.

30 35 7. An anchor comprising a shank formed of a plurality of complementary shell-like sections providing a weight chamber, and a grapple member on said shank.

In witness whereof I have hereunto set my hand.

JOHN A. HOLZAPFEL.
